*Primary Examiner—Alan P. Douglas**Assistant Examiner—A. D. Davis**Attorney, Agent, or Firm—Bell, Seltzer, Park & Gibson***[57] CLAIM**

The ornamental design for a long measuring tape, as shown and described.

DESCRIPTION

FIG. 1 is a perspective view of a long measuring tape which illustrates the new design;

FIG. 2 is a front plan view thereof;

FIG. 3 is a left side view thereof;

FIG. 4 is a right side elevation view thereof;

FIG. 5 is a top elevation view thereof;

FIG. 6 is a bottom elevation view thereof; and,

FIG. 7 is a rear plan view thereof.

The broken line showing of a tape is for illustrative purposes only and forms no part of the claimed design.

FIG. 1.

FIG. 5.

FIG. 6.

FIG. 7.
